UNITED STATES PATENT OFFICE.

JOHN KACHMAN, OF BERWYN, ILLINOIS.

CONNECTER.

Application filed January 5, 1927. Serial No. 159,179.

This invention relates to railways, and more particularly to a connector for securing together the meeting ends of sections of track used in electric toy railways.

5 One of the objects of the invention is to provide a connector for securing the ends of toy track sections together, that will absolutely prevent the sections from separating and will enable the sections to be easily and 10 quickly assembled without any interference from the connectors which are secured to the cross ties of the tracks, thereby overcoming misplacement or loss thereof.

A further object of the invention is to 15 provide a connector for track sections that is pivotally secured to the cross ties of the sections in a manner to be detachably secured to the cross ties of companion sections, to prevent misplacement or separation of the sections, and when said connectors are disposed 20 in their inoperative position they will in no way interfere with the packing of the sections in cartons and the like.

This invention also consists in certain 25 other features of construction and in the combination and arrangement of the several parts, to be hereinafter fully described, illustrated in the accompanying drawings and specifically pointed out in the appended 30 claims.

In describing my invention in detail, reference will be had to the accompanying drawings wherein like characters denote like or corresponding parts throughout the several views, and in which:

35 Figure 1 is a top plan view showing a pair of track sections secured and held together by my novel connectors.

Figure 2 is a similar view of a single track section showing my connectors disposed to inoperative position.

Figure 3 is a sectional view taken on line 3—3 of Figure 1.

Referring to the drawings in detail, it will 45 be noted that I have shown my novel connectors applied to a railway track of the three rail type but it will be obvious that they can be applied to tracks of the two rail type and operate with equal efficiency.

50 The letter A indicates the tracks which are secured and supported by cross ties B of the usual construction, and pivotally secured to the end cross tie of each section at a point adjacent one end thereof and between the 55 side edges of the top is the connector strip 1 with its pivot pin 2 extending through the

strip adjacent one end thereof in a manner whereby the strip is capable of swinging in horizontal plane as best shown in Figures 1 and 2 of the drawings.

Secured to and depending from the strip slightly beyond its center is a pin 3 which is adapted to be received in an adjacent cross tie of companion sections and for this purpose I have provided an opening 4 on one end of the end cross ties and these openings 4 are arranged in parallelism with the pivot pins 2 of the strips 1 as best shown in Figures 1 and 2 of the drawings.

From the above description and disclosure in the drawings, it will be obvious that my novel connector will positively secure the meeting ends of the sections to prevent misplacement or separation thereof, and by pivotally securing the connector, the same 70 may be swung out of the way when the tracks are associated and thereby in no way interfere with the sections when attaching them through the medium of the pin and socket connection, and when the sections are 75 so attached, the strip can be swung on its pivot and the pin 3 arranged in the opening 4 as clearly shown in Figure 1 of the drawings. Again, by pivotally securing the strips 1 in the manner shown and referred 80 to, it will be obvious that when they are arranged in inoperative position as shown in Figure 2, the sections can be conveniently 85 packed in cartons and the like without interference by the connectors.

It is thought from the forgoing description that advantages and novel features of my invention will be readily apparent.

I desire it to be understood that I may make changes in the construction and in the combination and arrangement of the several parts, provided that such changes fall within the scope of the appended claims.

What I claim is:

1. The combination with railway track 100 sections comprising rails and ties, of a connector for securing the sections together and comprising a strip pivotally secured to one cross tie of one section and adapted to be detachably received by one cross tie of a 105 companion section.

2. The combination with the sections of a railroad track and the cross ties thereof, of a connector including an elongated strip having one end pivotally secured to the end cross tie of one section, a pin depending from said strip and adapted to be received in an 110

opening formed in the end cross tie of a companion section.

3. The combination with the sections of a railroad track and the cross ties thereof, of a connector including an elongated strip pivotally secured to one end cross tie of one section adjacent the end of said tie and mid-

way the side edges of the top thereof, a pin secured to said strip slightly beyond its center and depending therefrom to be received in an opening formed in the adjacent end cross tie of a companion section. ¹⁰

In testimony whereof I affix my signature.
JOHN KACHMAN.
